UNITED STATES PATENT OFFICE.

HORACE L. KINGSLEY, OF RACINE, WISCONSIN.

LAUNDRY SUNDAY.

1,141,345.

Specification of Letters Patent. Patented June 1, 1915.

Application filed June 16, 1914. Serial No. 845,437.

To all whom it may concern:

Be it known that I, HORACE L. KINGSLEY, a citizen of the United States, and resident of Racine, in the county of Racine and State 5 of Wisconsin, have invented certain new and useful Improvements in Laundry Sundries; and I do hereby declare that the following is a full, clear, and exact description thereof.

- 10 My invention consists in what is herein particularly set forth with reference to the accompanying drawings and pointed out in the claims of this specification, its object being to provide simple, economical and efficient 15 readily detachable shape-retainers for stiff-starched and laundered cuff-ends of shirt-sleeves during the time the shirts are in the stock of a manufacturer, jobber, retailer or wearer, said shape retainers being 20 sundries for the laundry trade and designed to prevent breaking of the cuffs in which they are inserted, said cuffs being attached to the shirts instead of being what are known as detached cuffs.
- 25 Other forms of the same invention in its broadest sense are set forth in my application Serial No. 876,332, filed December 9, 1914.

Figure 1 of the drawings represents a 30 partly broken full line elevation of a laundry sundry designed as a detachable anti-break shape-retainer applied in a cuff-end of a shirt-sleeve shown by dotted lines; Fig. 2, a plan view of the shape-retainer in full 35 lines, dotted lines in the same figure serving to illustrate a cuff and a button by which the cuff is fastened on said shape-retainer; Fig. 3, an elevation of one, and Fig. 4, an elevation of another of a pair of members of the 40 shape-retainer aforesaid extended, the scale of the last two figures being less than that of the first two.

Referring by numerals to the drawings, 5 indicates a form-member and 6 a brace-member of a device in accordance with my 45 invention, both members being of sufficiently stiff suitable bendable material.

The form-member 5 is provided adjacent to its ends with button-holes 7, suitably disposed to register with the button-holes of a shirt-sleeve cuff. While I deem it preferable to paste or otherwise permanently fasten the ends of the form-member together, they may be left free if desirable.

55 The brace-member 6 is of material similar to the form-member, and it is transversely

scored at 8 to provide lapping end-flaps 9 that are pasted together or otherwise rigidly united, the remainder of said brace-member being bowed and pasted or otherwise rigidly secured to the form member 5 bent thereon, whereby the device as a whole has the form of a stiff-starched, laundered and uncreased closed cuff-end of a shirt-sleeve.

65 The device above specified is a laundry sundry designed to be placed in the attached stiff-starched and laundered cuff of a shirt-sleeve and held thereto by a button, or a tie-string (not shown) engaging the registering buttonholes of said sundry and cuff, whereby the shape of said cuff is retained unbroken while the shirt is in stock of a manufacturer, jobber, retailer or wearer.

70 From the foregoing, it will be understood that a stiff-starched, laundered, bowed and fastened cuff-end of a shirt-sleeve on a distending brace similar to that herein disclosed, is not liable to become broken or creased in packing or storing, such creasing 75 and soiling along the crease, being commonly experienced in the absence of a shape-retainer for the cuff such as I have provided.

80 Within the scope of my invention, as herein claimed, the form of the shape-retainer 85 for detachable engagement with a closed stiff starched and laundered attached cuff of a shirt-sleeve may be varied from that shown without departure from the spirit 90 of my invention or the function of the device as a brace to prevent creasing or breaking of the bow of said cuff.

I claim:

1. A distending brace having the form of the interior of a stiff-starched laundered and 95 bowed cuff-end of a shirt-sleeve and which is detachably retained in the cuff to fill the breakable portion of the same.

2. A distending brace consisting of a form member of sufficiently stiff bendable material and an inner hollow member to which the form member is fastened and bent to therewith have the general shape of a stiff-starched laundered and bowed cuff-end of a shirt sleeve with which said brace is temporarily engageable inside of the same to resist breaking down of the bow of said cuff under pressure thereon.

100 3. A device consisting of a form member of sufficiently stiff bendable material, and a 110 brace-member of similar material having lapping ends fastened together but other-

wise curvilinear in said form bent and fastened thereon, the device as a whole conforming to the general shape of a stiff-starched, laundered and uncreased closed 5 cuff-end of a shirt-sleeve with which it is engageable to retain the shape of the cuff.

4. A device consisting of a form of sufficiently stiff bendable material having the general shape of a stiff-starched, laundered 10 and uncreased closed cuff-end of a shirt-sleeve when the ends of said form are fastened together, said form being provided with buttonholes for registration with those of a cuff in which it may be detachably 15 secured.

5. A device consisting of a form member of sufficiently stiff bendable material having apertures therein adjacent to its ends, and a brace-member on which the form-member is 20 fastened and bent to therewith have the general shape of a stiff-starched, laundered and uncreased closed cuff-end of a shirt-sleeve when the ends of said form-member are fastened together; the apertures therein being 25 for registration with buttonholes of a cuff

in which said device may be detachably secured.

6. A device consisting of a form member of sufficiently stiff bendable material having apertures therein adjacent to its ends, 30 and a brace-member of similar material having lapping ends fastened together and the remainder thereof in the form of a bow on which the form member is fastened, the device as a whole having the general shape 35 of a stiff-starched laundered and uncreased closed cuff-end of a shirt-sleeve when the ends of said form-member are fastened together; the apertures therein being for registration with buttonholes of a cuff in which 40 said device may be detachably secured.

In testimony that I claim the foregoing I have hereunto set my hand at Racine in the county of Racine and State of Wisconsin in the presence of two witnesses.

HORACE L. KINGSLEY.
